his Attorney

UNITED STATES PATENT OFFICE.

LOUIS B. GIRARD, OF LOS ANGELES, CALIFORNIA, ASSIGNEE, BY MESNE ASSIGNMENTS,
TO JOHN P. WHITMORE, OF SOUTH PASADENA, CALIFORNIA, AND LOUIS B. GIRARD,
OF LOS ANGELES, CALIFORNIA.

WINDOW-SHADE-WINDING MECHANISM.

1,318,322.

Specification of Letters Patent.

Patented Oct. 7, 1919.

Original application filed October 2, 1916, Serial No. 123,436. Divided and this application filed March 12, 1917. Serial No. 154,163.

To all whom it may concern:

Be it known that I, LOUIS B. GIRARD, a citizen of the United States, residing at Los Angeles, in the county of Los Angeles, State 5 of California, have invented a new and useful Window-Shade-Winding Mechanism, of which the following is a specification.

This invention relates to means for winding up shades on their rollers after they have 10 been mounted thereon, this application being a division of my application for window shade mounter, filed Oct. 2, 1916, Ser. No. 123,436.

The main object of this invention is to 15 provide a machine whereby the winding of the shade upon the roller may be effected conveniently and rapidly.

Another object of the invention is to provide a machine of this kind in which the 20 shade winding means is in operation only when actually winding a shade upon its roller, being adapted to be easily thrown out of operation when the winding is completed.

A further object of the invention is to provide 25 means for lifting the roller clear of the supporting table, to enable winding of the shade thereon, and to automatically control the operation of the winding means by such lifting movement, so that the winding means 30 is brought into operation as the roller is raised.

Another object of the invention is to provide 35 means whereby the same machine may be utilized for winding shades upon rollers of different lengths.

Another object of the invention is to provide 40 means whereby rollers of different sizes may be accurately centered on the winding means so that the shade is wound smoothly and evenly on the roller.

The accompanying drawings illustrate a 45 machine embodying my invention and referring thereto:

Figure 1 is a plan view of the machine 50 and a portion of the table with a roller and shade in position thereon.

Fig. 2 is a section on line 2—2 in Fig. 1, with the roller removed.

Fig. 3 is a section on line 3—3 in Fig. 1.

Fig. 4 is an end view of the machine, taken 55 from the left end of Fig. 1.

Fig. 5 is a vertical section of the chuck for rotating the roller.

Fig. 6 is a vertical section of the pick-up 55 for the roller.

The shade roller support, winding mechanism, and operating motor therefor are preferably mounted on a table 1 as shown. The shade roller support 2 may be formed of channel iron with the flanges 2' thereof 60 extending upwardly so as to form guards for the roller 20 and retain it in proper position, as indicated in Fig. 3, and may be fastened to table 1 by means of screws, bolts or other suitable means 4.

The shade winding means is supported on a shaft 5, called the pickup shaft which is 65 rotatably mounted in front of table 1 in bearings 9 formed on brackets 6, said brackets being slidably secured or clamped to said 70 table by cap screws 7, passing through slots 8 in said brackets, so as to permit the shaft 5 to be moved toward or away from the table 1. Said shaft 5 is provided with an operating arm or handle 10 projecting from a 75 sleeve 11, which is mounted on the shaft by a key or spline 12 engaging in a longitudinal groove 13, so as to be slidable thereon but to cause shaft 5 to turn with handle 10. Sleeve 11 is further provided with an arm 80 14 extending rearwardly and having at its rear end a pick-up or roller engaging device 15 adapted to rest normally on roller support 2, and formed preferably as a head on a spindle 16 mounted to turn in a bearing 17 85 on arm 14, said head having a conical socket or recess 18 adapted to receive the pin at one end of the shade roller 20.

A driving chuck 22 is provided for engaging 90 the other end of the roller, said chuck being mounted on a mandrel 23, mounted to turn in bearings 24 and 24' on a chuck carrier 25, which is mounted on pick-up shaft 5 so as to turn therewith. The pickup shaft 5 with the pick up arm 14 and chuck carrier 25 95 carried thereby, constitute a pick up means mounted to swing vertically on the bearings 9, so as to raise the pick up arm and the chuck, together with the clutch device connected thereto, simultaneously, and thereby lift the shade roller bodily from the supporting bed and clear the latter sufficiently to enable winding of the shade on the roll without interference by the bed. A rubber friction ring 22' is secured in chuck 22 to 100 engage the end of the shade roller and cause 105

it to turn with said chuck. Said friction ring is provided with a recess 40, which is somewhat larger than the shade roller pin and has a conical portion 41 at its inner end, formed in the mandrel 23, the purpose of which will appear hereinafter. Bearing 24' is preferably provided with an end thrust ball bearing 26 for the chuck 22. A pulley 27 is fastened to mandrel 23 by set screw 39 screwing in the hub portion of pulley 27, and said pulley is provided with a groove 27' for receiving a round belt 28, which passes over a pulley 30 on the shaft 31 of a motor 32, which may be an electric motor, belt 28 being loose and therefore inoperative when the parts are in normal position. Pulley 30 is preferably provided with wide flanges 30' to retain the belt thereon when slack. A guard 33 is provided for pulley 27, being formed for example as a half ring flange on a cross arm 34 having a hub 34' adjustably mounted on an extension 35 of bearing 24, by means of a set screw 36.

A shade supporting platform 45 is provided on table 1, inclining upwardly and forwardly to near the level of the top of the shade roller when in position on the roller support 2, and adapted to hold the shade in position to be wound up on the roller.

30 The operation is as follows:

The shade roller 20 is placed upon the roller support 2, with the pin at one end inserted in the recess 40 of chuck 22 and the shade cloth is drawn from a pile of shade cloths 46 in position on platform 45 and fastened to the roller in any suitable manner, for example by hand, using a hammer and tacks, or as set forth in my application Ser. No. 123,436, of which this application is 40 a division. Recess 40 being larger than the pin at the end of the roller permits the pins of different size rollers to enter the same while the roller lies flat on the roller support so as to give a solid support for the operation of fastening the shade to the roller.

When this has been completed, the handle 10 is moved to the left on pick-up shaft 5, so as to cause pick-up device 15 to engage one end of the shade roller, the pin at this end 50 of the roller entering recess 18, which is conical in shape to receive pins of different size rollers and to center them accurately in the pick-up device during the winding operation. The operator holds the roller to the 55 left by a slight pressure upon handle 10, which causes the roller to be gripped between pick-up 15 and chuck 22, and then operates handle 10 so as to turn pick-up shaft 5 and raise chuck 22 and pick-up 15. This lifts 60 the shade roller off the support 2 and at the same time causes the pulley 27 to engage belt 28 so as to tighten said belt on said pulley and on pulley 30, which is operated by motor 32, and cause it to rotate pulley 27 65 and the chuck 22 connected thereto. The

shade roller is thereby rotated so as to wind the shade thereon, the operator exerting a slight pressure to the left on handle 10 with one hand to hold the shade tightly against the friction ring 22' on chuck 22, and pressing the shade with the other hand to cause it to wind tightly on the roller. The conical portion 41 of recess 40 enables it to receive the pins of different size rollers and to accurately center said roller on chuck 22 and cause it to rotate evenly and therefore to wind the shade smoothly.

Handle 10 is then released, lowering chuck 22 and pick-up 15, together with the shade and roller, onto support 2, and loosening belt 28 to such an extent that it is no longer able to turn pulley 27, which may therefore be said to be automatically thrown out of operation, when the shade is completely wound. The operator moves handle 10 to the right so as to remove pick-up 15 from the end of the shade roller, and the shade roller with the shade wound thereon is removed from the machine, which is then ready to receive another roller.

What I claim is:

1. In a shade winder, a table provided with means for supporting a shade roller, a horizontal shaft mounted to swing vertically on said table, a clutch support mounted on said shaft to turn therewith, a clutch mandrel mounted to turn in said clutch support, a clutch on said clutch mandrel, a driven wheel fast on said clutch mandrel, a motor, a driving member driven by said motor and adapted to come into operative engagement with said driven wheel when the clutch support is raised, and a pick-up device mounted to slide on said shaft and to turn therewith and provided with means for engaging an end of a shade roller to hold the other end of said roller into engagement with said clutch, and with an operating handle for operating the pick-up device longitudinally to engage the pick-up device with the roller and for moving the shaft to lift the pick-up device and clutch support to raise the roller bodily from the table and to bring the said driven wheel into operative relation with the said driving member to operate the clutch to rotate the shade.

2. In a shade winder, a table provided with means for supporting a shade roller, a horizontal shaft mounted to swing vertically on said table, a clutch support mounted on said shaft to turn therewith, a clutch mandrel mounted to turn in said clutch support, a clutch on said clutch mandrel, a pulley fast on said clutch mandrel, a motor, a belt driven by said motor and running over said pulley so as to be tightened thereon when the clutch support is raised, and a pick up device mounted to slide on said shaft and to turn therewith, and provided with an operating handle and with means for engaging

an end of a shade roller to hold the other end of said roller into engagement with said clutch.

3. In a shade winder, a shade roller supported and means for picking up the roller therefrom comprising a horizontal shaft, a clutch support carried thereby, a clutch rotatably mounted on said clutch support, a pick-up device mounted to slide on said shaft 5 and to turn therewith, and provided with a handle for operation thereof to bring the pick-up device against one end of the shade roller lying on its support, so as to grip the roller between the pick up device and the clutch and to then raise the pick up device 10 and the clutch simultaneously by rotation of the shaft, and means for driving said clutch.

4. A shade winder constructed according to claim 3, provided with driving means 20 brought into coöperative relation with said clutch to drive the same when the said clutch is raised by operation of said handle.

5. In a shade winder, a roller supporting

bed, a shaft extending parallel to said bed, and a pick-up device mounted to slide along 25 said shaft and to turn thereon, said pick up device having means for engaging one end of a shade roller and having a handle for moving it along said shaft to bring it into engagement with one end of the roller and for 30 turning it on said shaft to lift the roller from said bed.

6. A shade winder comprising a supporting bed for a shade roller, a table provided with means for supporting a shade in position for winding on said roller, means for rotating said roller to wind the shade thereon and means for lifting said roller bodily from said bed during the winding operation, to prevent interference of such bed with the 35 winding of the shade on the roller.

In testimony whereof I have hereunto set my hand, at Los Angeles, California, this 26th day of February, 1917.

LOUIS B. GIRARD.
